(57) **CLAIM**

The ornamental design for a suspension module wheel puller for suspension assemblies, as shown and described.

DESCRIPTION

FIG. 1 is a full side view of a suspension module wheel puller for suspension assemblies showing a left end cup, a right end follower and a threaded bolt therethrough with a fastening nut on the right end;

FIG. 2 is a full left end view of the suspension module wheel puller for suspension assemblies of FIG. 1 showing the head of the bolt and the follower cup; and,

FIG. 3 is a full right end view of the suspension module wheel puller for suspension assemblies of FIG. 1 showing the right end follower, a washer, and the fastening nut on the right end of the bolt.

The portions of the suspension module wheel puller for suspension assemblies shown in broken lines form no part of the claimed design.
